CLAIM

The ornamental design for a vacuum pump, as shown and described.

DESCRIPTION

FIG. 1 is a perspective view of a vacuum pump showing our new design;

FIG. 2 is another perspective view;

FIG. 3 is a bottom view;

FIG. 4 is a rear side view;

FIG. 5 is a right side view;

FIG. 6 is a front view; and,

FIG. 7 is a left side view.

The broken line showing of elements shown throughout the drawings is included for the purpose of illustrating environmental matter and forms no part of the claimed design.
